(57) **CLAIM**

The ornamental design for a wheel for automobile as shown and described.

DESCRIPTION

FIG. 1 is a front perspective view of a wheel for automobile, showing our new design; and,

FIG. 2 is a front elevation view thereof.

The claimed design is indicated by the relatively dark portion, while the relatively light and blurred portions are environmental and form no part of the claimed design.

1 Claim, 2 Drawing Sheets

FIG. 1

FIG. 2
